LEATHER CLEANING OR DEGLAZING
MACHINE

Floyd Falese, Carpentersville, Ill.

Application September 30, 1943, Serial No. 504,474

1 Claim. (Cl. 15—21)

My invention relates to machines or apparatus for cleaning or dressing leather or similar products.

My invention relates more particularly to a machine for preparing leather or leather goods such as shoes, boots, gloves, etc. for a dyeing or polishing operation by de-glazing or opening the pores in the leather.

In preparing leather goods such as those above mentioned for dyeing or for receiving a polish or other coating, it is necessary to thoroughly clean the goods and remove all of the pigments or glaze or any other finish that is on the leather so that the pores of the leather are opened thoroughly in order to receive the dye or other material with which the leather is to be treated.

Prior to my invention and discovery, it has been the custom in treating leather goods such as those mentioned for any of the various operations above mentioned, to resort to hand scrubbing with a brush and liquid.

It is therefore a principal object of my invention to provide an improved machine capable of cleaning or preparing leather for dyeing, polishing or receiving other treatment.

A further object of my invention is to provide a machine of the type described which embodies a rotatable brush and an automatic and manually controlled cleaning fluid for said brush.

A further object of the invention is to provide an improved machine of the type described wherein the cleaning liquid is directed on to the periphery of a rotating brush at such an angle that there will be no splash of the liquid over the operator or his clothing.

A further object of the invention is to provide an improved machine of the type described which is completely under the control of the operator, whereby a piece of leather goods such as a shoe may be subjected to the rotating brush, and the amount and speed of flow of the cleansing liquid can be manually or pedally controlled by the operator.

A further object of the present invention is to provide in a machine of the type described a liquid control means including a reservoir and continuously operating pump mechanism together with suitable check valves so that the liquid is at all times available at the rotating brush, and when the operator desires to cut off the flow of liquid it may be done instantly and the pump will direct the liquid back in to the reservoir.

A further object of my invention is to provide an improved drain and screen assembly associated with the rotatable brush so that all surplus liquid

will be strained and returned to the reservoir.

A further object of the invention is to provide an improved mechanism of the type described that is easily and simply constructed, yet one which will not become easily broken or out of order in spite of long and rough usage.

Other objects and advantages will be more apparent from the following description wherein reference is had to the accompanying drawings, upon which:

Fig. 1 is a side elevational view of my improved machine with a part of the hood broken in section to more clearly show the cleaning brush and nozzle;

Fig. 2 is a rear elevational view of the machine with parts of the housing and hood broken in section to more clearly show the operating parts;

Fig. 3 is a fragmentary front elevational view showing the nozzle and brush and the manner in which the fluid is sprayed over the surface of the brush;

Fig. 4 is a plan sectional view showing the reservoir, pump and associated mechanism, and

Fig. 5 is an enlarged vertical sectional view through the two-way valve and spraying mechanism.

In the embodiment of the invention which I have chosen to illustrate, I have shown a housing 10 which may be formed with the enclosing side walls 12, 14, 16 and 18 secured about suitable vertical angle members 20, 22, 24 and 26. A plurality of suitable leg members 28 are positioned below the base 30 which may include a horizontal shelf portion 32.

At the upper end of the frame 10 I provide the horizontal angle members 34 adapted to support a platform 36 which may be the lower part of a hood-shaped member 38 open in the front and extending generally upward and forward in the back. The hood shaped member 38 has a vertical dividing wall 40 which separates the same into the two compartments 42 and 44. In the compartment 44 I have provided a pair of upright bearing members 46 and 48 for supporting a horizontal shaft 50. At one end of the shaft 50 I provide a cloth or other suitable drying disc 52, and at the opposite end of the shaft in the compartment 42 I provide a cleaning brush 54.

The cleaning brush 54 may be constructed of a plurality of fine wire members 54' radially disposed about the shaft 50. As can be seen in Figs. 1 and 3, I provide a conduit 56 which extends from a reservoir 59, to be described later, to a point above the brush 54, and has a portion 58 directed

downwardly generally at a tangent to the diameter of the brush 54. The nozzle 60 formed in the end of the same may be flattened somewhat so that fluid being pumped through the conduit will be directed outwardly over generally the entire surface area of the brush 54.

Cleaning fluid which is to be directed to the brush 54 as above described, may be stored in a reservoir 59 positioned on the lower platform 32 of the machine, and pass through a conduit 62 to a pump housing 64. A reciprocating piston is provided in the pump housing driven by means of a piston rod 66 eccentrically connected to a disc 68 mounted on the end of the shaft 70. The shaft 70 and pulley 72 which is keyed to the shaft, may be suitably supported in a bifurcated bearing member 74. The drive for shaft 70 may be by means of a V-belt 75 connected to a small pulley 76 mounted on shaft 50. A larger pulley 78, also mounted on shaft 50, is driven by means of a V-belt 80 from the pulley 82 mounted on the motor shaft 84 of an electric motor 86. The motor 86 may be supported below the upper platform of the frame upon a base 88 supported by a plurality of hanging bolts 90. The bolts are surrounded by spacers 92 so that the motor may be firmly fixed to the frame to prevent undue vibration.

The fluid which is drawn from the reservoir by the pump is adapted to be directed outwardly through a one-way valve 94 in the conduit 96. This conduit may extend upwardly and connect by means of a T-member 98 with a vertical conduit 100.

The conduit 100 may contain a valve member which determines the amount and the rate of flow of fluid upwardly through the conduit 56 to the brush. This mechanism (see Fig. 3) may include a valve stem 102 provided with a head 104 adapted to sit upon a valve seat 106 in the T-member 98. The stem 102 passes through a portion 108 which has a bore 110 of a diameter slightly larger than the shank of the rod 102 so that when the valve head is removed from the seat 106 by being pushed downwardly, a portion of the fluid being pumped through conduit 96 will go upwardly through the bore 110, the T-member 112, and out through the conduit 114 which connects by suitable couplings to the conduit 56. It will be obvious, however, that a large portion of the fluid being pumped will be returned back to the reservoir through the conduit 100.

Means for operating the valve member 102 may include a foot lever 115 pivoted adjacent the rear of the machine on a suitable pivot member 116. The lever 114 may have a vertical rod 118 connected thereto. The rod 118 is adapted to be fastened to a lever 120 pivoted at 122 upon a bracket 124 that is mounted on the motor base 88. The lever 120 may be pivotally connected at 126 to a bifurcated block 128 secured to the upper end of the portion 130 of the valve rod 102. I provide a packing member 132 in the gland 134, and a compression spring 136 between the gland and the block 128 to normally raise the valve head to closed position as shown in Fig. 5.

In order to prevent the pump from becoming air bound, I provide a return passageway 132 upon the upper end of the pump cylinder to the upper end of the reservoir. A filling spout 134

may be connected to the reservoir and extend outwardly through the side wall of the housing for filling purposes.

From the description which has thus far been given, it will be apparent to those skilled in the art that I have provided an effective mechanism for providing a continuously rotating brush for dye preparing leather or for deglazing leather. It will be apparent that I have provided in connection with a continuously driven cleaning brush a manually or pedally controlled supply of cleansing fluid which, by reason of the by-pass valve construction described, permits a desired quantity and rate of flow of the fluid to the brush, continuously under the control of the operator. The balance of the liquid being pumped is being continuously returned to the reservoir.

The pump as described is also provided with a novel air line which connects the upper portion of the pump cylinder to the top of the supply reservoir, thus effectively preventing the pump from becoming air bound in the event that liquid should accidentally pass the piston leathers and enter the upper portion of the cylinder. The discharge nozzle 60 is so arranged with relation to the rotating brush that it directs the liquid stream at a tangent to the periphery of the brush, thus avoiding the splashing of the liquid upon the operator or any of the surrounding area.

30 The liquid which drops from the brush may be accumulated in a drain cup 11 which is provided with a fine screen member 13 and a return conduit 15 to the reservoir 58. Thus the liquid may be used over and over again, and as it is used 35 the same is continually drained out of the hood portion of the machine and returned to the reservoir.

From the above description it will be apparent to those skilled in the art that I have provided 40 a comparatively simple, yet efficient and effective mechanism for use in treating leather goods for the purposes described. While I have illustrated and described a specific embodiment of the invention, it will be apparent to those skilled in the 45 art that changes and modifications may be made in the exact details shown, and I do not wish to limit myself in any particular; rather what I desire to secure and protect by Letters Patent of the United States is:

50 A shoe cleaning machine comprising a housing having upper and lower platforms, said upper platform having a hood extending upwardly and outwardly leaving a forward opening, a fluid reservoir on said lower platform, a pump connected to said reservoir, a shaft mounted on said upper platform beneath said hood, a cleaning disc carried by said shaft, a motor in said housing rotating said shaft and operating said pump, a conduit connected to said pump extending upwardly in said hood behind said cleaning disc and over the top thereof and terminating in a nozzle portion directed at a tangent forwardly and down along the forward edge of said disc, whereby the fluid is directed inwardly of the hood, and pedal-controlled valve means for said conduit for controlling the flow of fluid to said nozzle.

FLOYD FALESE.
